DESIGN FOR A CAB-OVER-ENGINE FUEL TANK TRUCK

Alexis de Sakhnoffsky, Philadelphia, Pa., assignor to The White Motor Company, Cleveland, Ohio

Application January 21, 1937, Serial No. 67,193

Term of patent 7 years

To all whom it may concern:

Be it known that I, Alexis de Sakhnoffsky, subject of the Czarist regime of Russia, residing at Philadelphia, in the county of Philadelphia and State of Pennsylvania, have invented a new, original, and ornamental Design for Cab-Over-Engine Fuel Tank Truck, of which the following is a specification, reference being had to the accompanying drawing, forming part thereof.

Figure 1 is a perspective view of a cab-over-engine fuel tank truck of my design.

Figure 2 is a rear elevation thereof.

Figure 3 is a side elevational view of the rear half of the truck.

The side opposite that shown in Fig. 1 is a duplicate.

I claim:

The ornamental design for a cab-over-engine fuel tank truck as shown and described.

ALEXIS DE SAKHNOFFSKY.
